United States Patent Office.

JAMES McFEELY, OF NORTH WOBURN, MASSACHUSETTS.

Letters Patent No. 69,460, dated October 1, 1867.

IMPROVED WINDOW-SCREEN.

The Schedule referred to in these Letters Patent and making part of the same.

TO ALL WHOM IT MAY CONCERN:

Be it known that I, JAMES McFEELY, of North Woburn, in the county of Middlesex, and State of Massachusetts, have invented a new and useful Improvement in Window-Screens; and I do hereby declare that the following is a full, clear, and exact description thereof, which will enable others skilled in the art to make and use the same, reference being had to the accompanying drawings, forming part of this specification.

The present invention consists in so constructing the frame to a window or door-screen in such manner that water can be made or allowed to flow over the surface of the screen from top to bottom, whereby, while the dust, &c., is more perfectly excluded, the atmosphere of the room is rendered cooler and more pleasant.

In the accompanying plate of drawings my improvements in window-screens are illustrated, the figure being a central transverse vertical section through a window-screen constructed according thereto.

A, in the drawings, represents the frame to a window-screen, B. This frame, at its upper rail or strip C, is provided with a tank or reservoir, D, that extends along the length of the same. This tank D has a series of perforations, or one continuous opening, *a*, along each side of the screen B, so that water in such tank can pass down and over the screen in a sheet form or nearly so, falling into the tank or receptacle E, located and fixed in the proper position in the lower rail F, to the frame A, from which it escapes at the pipe G. By the above-described construction of a window or door-screen, it is obvious the purposes of the present invention are secured.

I claim as new, and desire to secure by Letters Patent—

The perforated or slotted tank D, reservoir E, and spout G, in combination with the frame A and screen B, substantially as described for the purpose specified.

The above specification of my invention signed by me this 16th day of July, 1867.

JAMES McFEELY.
